John T. Young
ATTORNEY.

UNITED STATES PATENT OFFICE.

CHARLES E. YOUNG, OF ROCHESTER, MINNESOTA.

BUTTON.

Application filed March 27, 1928. Serial No. 265,035.

The object of the invention is to provide a button which may be readily attached to wearing apparel without the necessity for the use of thread; to provide a button of this character which, when desired, may be readily detached from the goods by which it is carried, and attached elsewhere; to provide a button in which there is a positive connection between the button and its stem with the stem loosely engaged with the button so that there may be relative swinging movement between the two whereby the possibility of damage to the button, when attached to wash goods and when the latter is passed through a clothes wringer, is reduced to a minimum; and to provide a device of this character which is of simple form and therefore susceptible of cheap manufacture and low marketing cost.

With this object in view, the invention consists in a construction and combination of parts of which preferred embodiments are illustrated in the accompanying drawings, wherein:—

25 Figure 1 is a central vertical sectional view through the invention.

Figure 2 is a top plan view.

Figure 3 is a sectional view on the plane indicated by the line 3—3 of Figure 1.

30 Figure 4 is an elevational view of the stem with the button attaching means mounted therein.

Figure 5 is a view similar to Figure 1 but showing a modified form.

35 Figure 6 is a top plan view of the structure of Figure 5.

Figure 7 is a perspective view of a tool, such as is used in the attachment of the button to goods.

40 Figure 8 is an actual view on the plane indicated by the line 8—8 of Figure 1.

In order to provide for a loose or swinging or pivotal connection between the button 10 and its stem 11, the latter, which may be of 45 pearl, rubber, celluloid, bone, metal or any other desired material and which is formed with a head 12, has the head enclosed with a cap 14 with which there are formed the wings 15. Prior to the attachment of the stem with 50 the button, the wings lie flat against the shank of the stem and the latter is inserted through the eye of the button until the cap 14 abuts the upper face. The wings 15 which are pliable, are bent outwardly and up around the annular flange 16 bounding the eye of the button on

the under face. By this construction the cap becomes fixedly connected to the button and the stem is engaged with the cap, but loosely, there being sufficient play between the cap and the head 12 to permit the cap and with it the button to swing loosely on the stem.

The stem at the end remote from the head 12 is of hemispherical shape as indicated at 17, to facilitate the passage of the stem through a hole made in a garment or piece of goods for the reception of the button, the hole being perfectly made by an awl such as indicated at 18.

The stem is shouldered back of the extremity 17, as indicated at 19, this shoulder being engaged by the spring jaws 20 when the retainer 21 is attached. The retainer 21 is of disk form and is provided with an eye 23 through which the extremity 17 of the stem may pass. On the under face of the retainer is attached a thimble 23 to shroud or surround the extremity 17 when the retainer is engaged with the stem. This thimble is slotted laterally on diametrically opposite sides as indicated at 24 to provide clearance spaces for the spring jaws 22 which are merely the free terminals of the spring 25 which is supported by the flange 26 of the retainer which is extended downwardly to the plane of the dome of the thimble.

In Figures 5 and 6 a modification of the invention is illustrated, this modification concerning only the means of attaching the stem 11^a to the button 10^a. In this form of the invention, the head 12^a of the stem is made larger than the eye of the button and when the stem is inserted through the eye, it is retained in loose engagement with the button by a clip 27 which diametrically spans the head of the button and is provided with terminal pliable ears 28 inserted through slots formed in the button at diametrically opposite sides of the eye.

The retainer used in connection with the button illustrated in Figures 5 and 6 is identical with that used in connection with the other form illustrated.

In attaching buttons constructed in accordance with the invention, a cloth is punctured at the desired points with the awl 18 and the buttons are attached by inserting the stems in the perforations thus made, the retainers being attached to the conical extremities of the stems after such insertion. By the use of the awl illustrated the warp and woof threads

are separated to form the stem receiving hole and are not severed as they would be by use of a punch. While the invention is illustrated as having the head of the stud and the 5 cap above the plane of the top or outer face of the button, it is obvious that the eye of the latter particularly where the button is made of solid material, may be countersunk so that they leave the cap and head flush with the 10 outer face of the button.

The invention having been described, what is claimed as new and useful is:—

A device of the kind described comprising a button, a stem connected at one end with

the button, and a retainer detachable engaged with the remaining end of the stem, the stem having a tapered terminal and a shoulder just back of the same, and the retainer having a thimble in which the tapered terminal is received, and spring jaws engaging said shoulder, the spring jaws consisting of the free terminals of a spring carried by the retainer, and the thimble being slotted on diametrically opposite sides to provide clearance spaces for said jaws. 15

In testimony whereof he affixes his signature. 20
